UNITED STATES PATENT OFFICE

155,726

DESIGN FOR A HOUSING FOR A DICTATING MACHINE

William J. O'Neil, New York, N. Y., assignor to Dictaphone Corporation, Bridgeport, Conn., a corporation of New York

Application February 11, 1949, Serial No. 800

Term of patent 14 years

(Cl. D64—11)

To all whom it may concern:

Be it known that I, William J. O'Neil, a citizen of the United States and a resident of the city of New York, in the county of New York and the State of New York, have invented a new, original, and ornamental Design for a Housing for a Dictating Machine, of which the following is the specification, reference being had to the accompanying drawings, forming part thereof.

Figure 1 is a perspective view of the front and right-hand side of a housing for a dictating machine, showing my new design;

Figure 2 is an elevation of the right-hand side thereof;

Figure 3 is a front elevation thereof;

Figure 4 is a rear elevation thereof; and

Figure 5 is an elevation of the left-hand side thereof.

The dominant features of my design reside in the portions shown in full lines in the drawings.

I claim:

The ornamental design for a housing for a dictating machine, substantially as shown and described.

WILLIAM J. O'NEIL.
